(57) **CLAIM**

The ornamental design for: fuel checker device, as shown and described.

DESCRIPTION

FIG. 1 is a diagrammatic left side elevational view showing my new design for a fuel checker device, the right side being a mirror image thereof;

FIG. 2 is a front elevational view thereof;

FIG. 3 is a rear elevational view thereof;

FIG. 4 is a top elevational view thereof; and,

FIG. 5 is a bottom elevational view thereof.

1 Claim, 1 Drawing Sheet

FIG. 4

FIG. 3

FIG. 1

FIG. 2

FIG. 5
